UNITED STATES PATENT OFFICE.

JAMES M. ULSH, OF LANCASTER, PENNSYLVANIA.

HARROW.

No. 807,700.

Specification of Letters Patent.

Patented Dec. 19, 1905.

Application filed December 6, 1904. Serial No. 235,681.

To all whom it may concern:

Be it known that I, JAMES M. ULSH, a citizen of the United States, residing at Lancaster, in the county of Lancaster and State of Pennsylvania, have invented a new and useful Harrow, of which the following is a specification.

This invention relates to harrows of the spring-tooth-lever type, exemplified, for instance, in my copending application Serial No. 216,128, in which many of the features of my present invention are disclosed.

The object of the invention to be particularly emphasized herein is to equip a harrow of the character specified with a plurality of tooth-bars arranged in sections at opposite sides of the longitudinal center of the harrow and each equipped with a plurality of teeth arranged to be simultaneously adjusted either vertically or horizontally, the vertical adjustment being effected by the rotation of the tooth-bars and designed to regulate the depth of cut and the horizontal adjustment being effected independently of the tooth-bars and designed to present the teeth either edgewise or at an angle to the line of draft or directly across the line of draft, as desired.

A still further object is to provide improved mountings for the individual tooth-bars and novel means for bracing the bars to reduce the liability of breakage.

Subordinate objects of the invention will appear more fully hereinafter.

In the accompanying drawings, Figure 1 is a plan view of my harrow with the teeth arranged directly across the line of draft. Fig. 2 is a side elevation thereof. Fig. 3 is a plan view of one of the tooth-bars, showing the teeth disposed edgewise to the line of draft. Fig. 4 is a sectional view, on a somewhat-enlarged scale, showing the mounting of one of the teeth. Fig. 5 is a detail view showing one of the shifting bars and its bracket. Fig. 6 is a detail perspective view of one of the tooth-holders applied to a tooth-bar. Fig. 7 is a detail view of a tooth and its brace, and Fig. 8 is a detail sectional view of a modified form of tooth-holder.

Like numerals indicate corresponding parts in the several views.

1 and 2 indicate the side sections of an angle-iron runner-frame located at opposite sides of a central frame member 3, constituting one element of a hinged connection between the frame-sections. Mounted on the runners 4 and 5 of the runner-frame are a plu-

rality of standards 6, between the upper ends of which and the central frame member 3 are disposed rotary tubular tooth-bars 17. So far as the present invention is concerned, the particular form of mounting for the tooth-bars is immaterial, it being sufficient to say that each bar is designed to rotate on its axis and that the several bars at each side of the central member 3 move bodily with the hingedly-connected sections of the runner-frame. The frame structure of the harrow is completed by the provision of front and rear caster-wheels 19 and 20, mounted in wheel-frames 21, secured to and supporting the opposite ends of the central member 3, as shown in Fig. 2.

Upon each of the tooth-bars 17 is mounted a series of harrow-teeth 24, which, as has been stated, are designed to be elevated and depressed and to be adjusted laterally for the purpose of disposing them across the line of draft edgewise thereto or at an intermediate angle, as desired. The vertical portion or shank 24^a of each harrow-tooth is received by a vertically-disposed transversely-rectangular tooth-holder 25, the front wall of which is formed with an opening to accommodate the tooth-retaining bolt 26. From the front side of the tooth-holder 25 extend a pair of horizontal bearing-ears 27, which receive between them a bearing-lug 28, to which they are connected by a vertically-disposed hinge-bolt 29, constituting the axis from which the tooth-holder 25 is swung laterally to adjust the teeth. The lug 28 extends rearwardly from the tooth-bar, being carried by an integral split collar 30, encircling the bar and secured by a clamping-bolt 34, as shown in Fig. 4. To prevent the split collar 30 from turning on the tooth-bar 17, said collar is provided with an inwardly-extending lug 30^a, received within an opening 30^b in the bar. From the front side of each tooth-holder also extends an arm 35, the front ends of the several arms associated with each tooth-bar being connected by a shifting bar 36, which may be shifted longitudinally for the purpose of swinging the several tooth-holders when it is desired to effect a lateral adjustment of the teeth. The shifting bar is retained in its adjusted positions by a bolt 37, passed through a pair of bearing-lugs 38 and through the shifting bar arranged to slide between the lugs. The lugs 38 constitute part of a bearing-bracket 39, mounted on the tooth-bar by means of a split collar 40, encircling the bar

and retained by a bolt 41. (See Fig. 5.) If it is desired to present the teeth broadside to the ground or across the line of draft, they are positioned as shown in Fig. 1. If, however, it is desired to present the teeth edge-wise to the line of draft, each alternate shifting bar 36 is moved longitudinally to swing the tooth-holders 25 to the positions indicated in Fig. 3, where they are retained by passing each of the bolts 37 through one of a series of openings 42 in each of the shifting bars. The other shifting bars are similarly adjusted, but in the opposite direction, so that while all of the teeth will be located edgewise to the line of draft the teeth of alternate rows will be oppositely disposed or curved. Obviously if it is desired to retain the teeth in intermediate positions—that is to say, in angular relation to the line of draft—the desired end may be attained by securing the shifting bar in an intermediate position. Thus it will appear that the series of teeth carried by each tooth-bar may be simultaneously adjusted laterally on vertical axes. In addition to this adjustment I provide means whereby all of the teeth of each side or section of the harrow may be simultaneously elevated or depressed, this end being attained by swinging the teeth from horizontal axes, or, in other words, by the rotation of the several tooth-bars. To effect this latter adjustment, each set of tooth-bars—to wit, the bars at each side of the harrow—are equipped with radial arms 43, connected by a bar 44, carrying a toothed segment 45, arranged to be engaged by the latch 46, carried by a tooth-adjusting lever 47, preferably formed by elongating one of the arms 43, as shown in Fig. 2. In use the teeth will first be set with respect to the line of draft in accordance with the character of work to be done. During the harrowing the depth of cut may be easily regulated by the manipulation of the levers 47 according to the hardness of the particular ground being worked and the depth of cut desired.

It will now be seen that the harrow is characterized by spring-teeth adjustable both vertically and horizontally and so mounted upon elevated tooth-bars extending in opposite directions from a single suitably-supported central frame-bar that a maximum clearance permitting the free passage of the harrow over rubbish and obstructions will be secured.

Another feature of the invention disclosed more particularly in Figs. 2, 4, and 7 is a novel form of tooth-brace 24^b in the form of a metal bar imposed against the rear side of the tooth and conforming to the contour thereof. This brace extends from the upper end of the shank to a point approximately one-third of the length of the tooth proper and secured by the bolt 26, which passes through this brace or reinforce, as well as through the shank of the tooth. The lower end of the brace 24^b is preferably tapered, as

shown in Fig. 7, and it will be seen that by providing the tooth with this bracing or reinforcing member the liability of breakage is reduced to a minimum without unduly stiffening that portion of the tooth which is intended to have more or less resiliency or spring.

In some instances it may be unnecessary to provide for the horizontal adjustment of the teeth, and in that event they are mounted as shown in Fig. 8, the tooth-holder 25 being formed integral with or rigidly connected to the split collar 30 instead of having hinged connection therewith, as in Fig. 4.

Before concluding attention is directed to the fact that my harrow is not of that type in which the teeth are mounted to trail rearwardly from the bars and are pivoted to the bars by means of pintles disposed at right angles to the teeth, so that the latter may be swung to cause them to trail directly in the line of draft or to be disposed longitudinally at an angle to the line of draft. On the contrary, the shifting of the teeth of my harrow relative to the tooth-bars is not designed to change their longitudinal direction, which is always substantially vertical when the harrow is in use, but is designed to present the flat front faces of the harrow-teeth either directly across the line of draft at an angle thereto or completely edgewise to the line of draft, as desired. This end is attained, as already stated, not by swinging a tooth on an axis at a right angle thereto, as in harrows of the trailing-tooth type, but by shifting the tooth around an axis extending in the same general longitudinal direction as the tooth, this or equivalent expressions employed in the claims being intended to include a pivotal mounting the axis of which may be either in line with the longitudinal axis of the tooth or substantially parallel with a line following the general longitudinal direction of the tooth.

It is thought that from the foregoing the construction and operation of my harrow and the many advantages accruing therefrom will be clearly comprehended; but while the present embodiment of the invention appears at this time to be preferable I wish to be distinctly understood as reserving the right to effect such changes, modifications and variations of the illustrated structure as may come fairly within the scope of the protection prayed.

What I claim is—

1. A harrow, comprising a supporting structure and adjustable teeth arranged for presentation across the line of draft or edge-wise thereto.

2. A harrow, including a supporting structure, a plurality of teeth, and means for simultaneously adjusting said teeth to present them across the line of draft or edge-wise thereto.

3. A harrow, including a supporting structure, a plurality of harrow-teeth adjustable for presentation across the line of draft or edgewise thereto, means for effecting such adjustment, and means for effecting the simultaneous vertical adjustment of the teeth. 5
4. A harrow, including a supporting structure, a plurality of teeth mounted to swing from horizontal and vertical axes, means 10 common to a plurality of teeth for effecting their horizontal adjustment, and separate means common to said teeth for effecting the vertical adjustment thereof.
5. A harrow, including a supporting structure, a plurality of adjustable tooth-bars, a plurality of vertically-disposed teeth mounted on each bar, adjusting means common to the teeth carried by each bar for shifting said teeth around substantially vertical axes, and 15 separate adjusting means common to the several bars.
6. A harrow, including a plurality of rotary tooth-bars, adjusting means common thereto, and a plurality of teeth pivotally connected to each bar and shiftable around axes disposed substantially parallel with the shanks of said teeth. 20
7. A harrow, including a plurality of rotary tooth-bars, adjusting means common thereto, a plurality of teeth pivotally connected to each bar, and means for simultaneously swinging a plurality of teeth independently of the bars and around axes extending in substantially the same longitudinal direction as the teeth. 30
8. A harrow, including a plurality of horizontal rotary tooth-bars, a plurality of substantially vertical teeth carried by each bar and mounted to swing from vertical axes, an 35 arm associated with each tooth, a shifting bar connected to the several arms, means carried by each tooth-bar for retaining the shifting bar associated therewith in its adjusted positions, and means common to the several tooth-bars for rotating the same to raise and lower the teeth.
9. A harrow, including a supporting structure, a tooth-bar, a bracket secured to the tooth-bar, a tooth-holder pivoted to the bracket, and means for swinging the holder to adjust the tooth. 50
10. A harrow, including a supporting structure, a tooth-bar, a bracket carried by the tooth-bar and having a bearing-lug, a tooth-holder having a pair of bearing-ears pivoted to the bearing-lug, means for securing a tooth in the holder, and an arm extending from the holder to facilitate the adjustment thereof. 55
11. A harrow, including a supporting structure, and a tooth mounted to swing from an axis extending in the same general longitudinal direction as the tooth to permit the presentation of the latter directly across the line of draft or at an angle thereto. 60
12. A harrow, including a supporting structure, a tooth mounted to swing from a horizontal axis to effect its elevation and depression, said tooth being also mounted to swing from another axis disposed substantially perpendicular to the ground when the tooth is in its fully-depressed position. 70
13. A harrow, including a supporting structure, vertically-disposed teeth mounted to turn on vertical axes, horizontal arms associated with the teeth, and shifting means common to a plurality of said arms. 75
14. A harrow, including a supporting structure, a plurality of harrow-teeth arranged for presentation across the line of draft or edgewise thereto, and means for simultaneously raising or lowering said teeth. 80
15. A harrow, including a plurality of teeth mounted to turn on axes disposed in the same general longitudinal direction as the teeth, and means for raising or lowering said teeth. 85
16. A harrow, including a supporting structure, a tooth-bar mounted to turn on a horizontal axis, and a plurality of teeth adjustable with the bar and each mounted to turn on an axis disposed transverse to the tooth-bar and in the general longitudinal direction of the tooth. 90
17. A harrow, including a supporting structure, a horizontal rotary tooth-bar, a plurality of teeth carried by the bar and arranged to swing from axes disposed in the same general longitudinal direction as the teeth, and shifting means common to said teeth. 95
18. A harrow, including a plurality of rotary tooth-bars, adjusting means common to the several bars, a plurality of teeth connected to each bar and mounted to swing from axes disposed in the general longitudinal direction of the teeth, and means common to the teeth of each bar for swinging them relative to the bar. 100
19. A harrow, including a supporting structure, and a tooth carried thereby and mounted to swing from an axis parallel with the shank of the tooth. 110
20. A harrow, including a horizontal tooth-bar, a vertically-disposed tooth-holder having the form of a boxing at one side of the bar, two substantially semicircular yielding members encircling the tooth-bar and having connection with the front of the tooth-holder intermediate of the ends thereof, a bolt connecting the ends of the two yielding members and located at the opposite side of the tooth-bar from the tooth-holder, and a projection extending into engagement with the tooth-bar from one of the members and adapted to be withdrawn from engagement with the bar by the outward spring of said member when the bolt is loosened. 115
21. A harrow, including a tooth-bar, and a holder adapted to receive the shank of a tooth, and connected to the tooth-bar by means permitting the swinging of the tooth-holder. 120
- 125
- 130

from an axis disposed longitudinally of the holder and transversely of the tooth-bar.

22. A harrow, including a tooth - bar, a tooth - holder, a tooth having its shank secured in the holder, and a pivotal connection between the tooth-holder and the bar, the axis of said connection being disposed substantially parallel with the tooth-shank.

23. A harrow, including a tooth-bar, a series of pivoted teeth carried by the bar, a shifting rod common to said teeth, and a retaining device for the shifting rod, said retaining device including a split collar attached to the tooth-bar and means for connecting the rod and collar.

24. A harrow, including a tooth-holder having the form of a boxing, a spring-tooth having a straight shank retained in the boxing, a reinforcing-strip opposed to the rear side of the tooth and its shank and likewise retained in the boxing, and a bolt passed through the boxing, the tooth-shank and the reinforcing-strip to retain said elements in proper relation.

25. A harrow, including a support and a

tooth movable to present its flat front face directly across the line of draft, or at an angle thereto, with one side edge of the tooth disposed farther forward than the other.

26. A harrow, including a tooth - bar 30 mounted to rock, a tooth pivotally connected to the bar, the active portion of said tooth having the form of a longitudinally-curved flat spring with its lower extremity normally directed forwardly and its flat front face disposed across or transverse to the line of movement of the tooth through the ground, said tooth being movable on its pivot to present its front flat face at an angle to the line of draft or movement, with one side edge of 35 40 said active portion of the tooth farther advanced than the other.

In testimony that I claim the foregoing as my own I have hereto affixed my signature in the presence of two witnesses.

JAMES M. ULSH.
